COMBINED TOY TOP AND LAUNCHER

James Nolen Holsombach, 365 150th Ave.,
Madeira Beach, Fla.

Filed Apr. 6, 1964, Ser. No. 79,353

Term of patent 3½ years

(Cl. D34—15)

Fig. 1

I claim:

The ornamental design for a combined toy top and launcher, as shown.
